UNITED STATES PATENT OFFICE.

THOMAS GRUBB, OF JOHNSTON CITY, ILLINOIS.

MAIL-HANDLING APPARATUS.

1,346,018.

Specification of Letters Patent.

Patented July 6, 1920.

Application filed December 29, 1919. Serial No. 347,955.

To all whom it may concern:

Be it known that I, THOMAS GRUBB, a citizen of the United States, residing at Johnston City, in the county of Williamson 5 and State of Illinois, have invented new and useful Improvements in Mail-Handling Apparatus, of which the following is a specification.

This invention relates to an improvement 10 in mail handling apparatus, of that type designed for use in post offices, wherein the mail is distributed in independent boxes in accordance with an alphabetical arrangement. 15 The improved apparatus is designed to provide a series of independent sets of boxes, each set of boxes to include a sufficient number of independent boxes to take care of a certain part of the mail under the alphabetical distribution. For example, one set of boxes will take care of all mail classified 20 under the letter A, the next set of boxes the mail classified under the letter B and so on, the boxes of each set being further divided 25 in accordance with a more specific classification. Each set of boxes is mounted for independent travel upon a track way and the respective track ways are arranged to converge to a point of distribution, as for example 30 the delivery window of the post office. The postal clerk by the operation of suitable mechanism can direct the movement of any particular set of boxes from a remote point to a position convenient to him, so that he may select from the proper 35 box the mail called for. The boxes of each set arranged in vertical rows and each row is independently movable longitudinally thereof, with a compensating or balancing means 40 between the rows of any one set, whereby the postal clerk may readily elevate the particularly desired set in order that he may conveniently reach the lower box of such set to remove the mail thereof.

45 The series of boxes are preferably arranged on track ways which converge to a point of distribution, and diverge therefrom so that at the rear or remote point, which in the normal position of the boxes, the respective sets of boxes are so separated as 50 to be readily accessible for the distribution of mail thereto. Upon the proper operation however, any one particular set of boxes may be brought to the converging point,

which is of course within convenient reach of 55 the postal clerk. Therefore all boxes normally positioned to readily permit the distribution of mail thereto, may at the will of the operator be brought to a single position convenient of access in order that the 60 desired mail may be readily and quickly found and delivered to the addressee.

In the drawings:

Figure 1 is a view in rear elevation of the improved apparatus.

Fig. 2 is a plan of the same.

Fig. 3 is a view in front elevation of the improved apparatus.

Fig. 4 is a sectional view on line 4—4 of Fig. 5.

Fig. 5 is a view in elevation of the frame in which the particular set of boxes is housed.

Fig. 6 is a view in rear elevation of one set of boxes, illustrating particularly the 75 compensating or balancing means for the boxes to permit of their vertical movement.

Fig. 7 is an enlarged view in elevation illustrating the means whereby the operator may direct a particular set of boxes from 80 the inoperative position to the operative position.

Fig. 8 is an enlarged detail showing the track mounting of one set of boxes.

The improved mail handling apparatus 85 comprises a series of track ways 1, arranged upon the floor or other support, these track ways converging from their rear toward their forward ends, and terminating at an upright post 2. An appropriate overhead 90 support 3 is provided from which, above each track, extends a beam 4, the forward ends of which converge and terminate at the post 2. Each beam 4 carries a trackway 5 and the trackways 5 are of course located 95 immediately above the underlying respective trackways 1. Each corresponding pair of trackways, that is the lower trackway and an upper trackway are designed to slidably support what will be hereinafter termed a 100 set of boxes, and these boxes are mounted in a frame work to insure their movement along the trackway as a unit while permitting their independent movement vertically at will. This frame work comprises a series 105 of metallic casings 6 having a rear wall 7 and side walls 8 corresponding in height to the number of superimposed boxes of any

one vertical row. The forward ends of the side walls 8 terminate in lateral flanges 9, and the frames 6, corresponding in number to the desired number of rows of boxes of one unit are secured together by a backing 10, fixed to their rear walls 7. Clamps 11 engage the flanges 9 of the side walls 8 of adjacent frames so that the frames constitute in effect hollow casings corresponding in number to the number of rows of boxes in any particular set and are secured together at their forward and rear ends. The boxes 12 are arranged within the particular frames 6, and these boxes are preferably of a size to receive the character of mail for which they are intended, as papers, letters or the like, and fit between the walls 8 and within the flanges 9, thus being slidably held in the respective frames. The frames 6 at the upper and lower end are provided with means, preferably roller bearing members 13 adapted to coöperate with the respective trackways so that the frames and the boxes contained are slidably mounted on the respective trackways. In this arrangement of the parts the boxes open laterally of the track, that is the backs 7 of the frames 6 are parallel to the track, so that an end of a series of boxes is presented toward the post 2, as will be apparent from the drawings.

Means are provided whereby any series of boxes, of which there may be any number, as will be understood, may, at the will of the operator, be forced lengthwise of the track, from their remote position, that is from a position at the diverging end of the track to a position immediately adjacent the post 2 or at the converging end of the track. In the latter position, the respective boxes are within convenient reach of the postal clerk so that he may remove the mail therefrom at will. The means for operating the particular sets of boxes includes a lever 14 pivotally supported at 15 at its lower end from one of the uprights of the fixed frame, the upper end of said lever being connected by a cable 16, passing over a suitable idler to a position pendent on the post 2, that is within the reach of the operator. Each cable 16 will be marked at its operating end to indicate the particular set of boxes with which it coöperates. A pivoted latch lever 17 is mounted upon the frame support and this lever is adapted to engage the catch 18 for locking the set of boxes in their rearmost or inoperative position. The forward end of the latch lever 17 is formed to be engaged by the lever 14 so that upon the operation of said lever by the cable 16 the latch lever will be released from the catch 18 and the set of boxes freed. A plunger bar 19 is slidably mounted in the upright and its rear end is provided with a head 20 to be engaged by the lever 14 and the forward end of said bar 19 is in position to engage the frame at the

rear end of the particular set of boxes. The bar 19 is held retracted by a spring 21.

Therefore, the operator desiring a particular set of boxes to be brought to the operative position, will actuate the appropriate cable 16. This draws upon the lever 14 and releases the catch 18 and by striking the head 20 of the bar 19 forces said bar forwardly against the boxes, and therefore propelling said set of boxes along the respective track ways until it reaches the position adjacent the post 2.

As before stated the rows of boxes are vertically movable in the frames so that the mail in the lower box may be removed without bending over and I provide means for counterbalancing one row of boxes by another row so as to make the row movable with but little effort. The rear parts of the frames are provided with slots 22 which are arranged adjacent the upper and lower ends of the frames and these slots act as guides for the rows of boxes by receiving the ends of shafts 23 carried by the said rows. These slots and shafts also act to limit the vertical movement of the rows of boxes. The lower shaft carries pulleys 24 and a cable 25 has one end connected to the frame at the upper part thereof, as at 26 and said cable passes around the pulley 24 of the first row of boxes then upwardly around a stationary pulley 27, then downwardly around the pulley 24 of the second row of boxes, upwardly again and around a stationary pulley 28, downwardly again around the pulley 24 of the third row and then upwardly to the top of the frame, where it is connected at 29. The length of the cable is such that one of the rows of boxes will be held in raised position while the other two rows are in lowered position. It will thus be seen that when one of the lower rows of boxes is raised the upper row will be lowered. In this way the rows of boxes may be raised with but little effort so that when it is desired to remove mail from the lower boxes it is simply necessary to raise the rows to bring said lower boxes in a position where the mail therefrom may be removed without bending.

It is thought from the foregoing description that the advantages and novel features of my invention will be readily apparent.

I desire it to be understood that I may make changes in the construction and in the combination and arrangement of the several parts, provided that such changes fall within the scope of the appended claims.

Having thus described the invention what is claimed is:—

1. A mail handling apparatus comprising a series of boxes arranged in sets, means for adjusting the sets vertically, independent horizontal trackways for each set and means whereby any particular set may be directed

from one point to another along the trackway.

2. A mail handling apparatus comprising a series of boxes arranged in sets, means for adjusting the boxes vertically, independent horizontal trackways for each set, rollers at the upper and lower ends of each set of boxes for engaging the trackways and means whereby the boxes of any one set may be moved along its trackway from one position to another.

3. A mail handling apparatus comprising a series of upper and lower trackways, a set of boxes supported independently along the trackways, each set of boxes comprising independently movable vertical rows of boxes, means for locking the boxes at one end of the trackway and means operable from the other end of the trackway for releasing the lock and forcing the set of boxes lengthwise of the trackway.

4. A mail handling apparatus comprising a series of upper and lower trackways, a set of boxes supported independently along the trackways, each set of boxes comprising independently movable vertical rows of boxes, means for locking the boxes at one end of the trackway and means operable from the other end of the trackway for releasing the lock and forcing the set of boxes lengthwise of the trackway, said means comprising a lever, a cable for operating the same, means

on the lever for releasing the lock and a spring pressure bar put under tension in the movement of the lever to release the lock. 35

5. A mail handling apparatus comprising a series of boxes arranged in sets, a frame for each set of boxes, trackways for movably supporting the frames, means for directing the frames longitudinally of the trackways, each set of boxes comprising independently movable vertical rows of boxes and cable connections between the boxes of each vertical row of the sets whereby in the movement of one set of boxes the weight of 45 the others will compensate for such movement.

6. A mail handling apparatus comprising a horizontal trackway, frames movably supported thereon, means for securing the 50 frames together, and a vertical row of boxes mounted in each frame and movable vertically therein.

7. A mail handling apparatus comprising a series of trackways, a mail box receiving 55 frame movable on each trackway and including rear walls, side walls and flanges to overlie the forward edges of the boxes, a row of boxes vertically slidably in the frame and connections between the frames and the 60 boxes to limit the vertical movement of any particular row.

In testimony whereof I affix my signature.
THOMAS GRUBB.
